CLAIM

The ornamental design for a container with center divider, as shown and described.

DESCRIPTION

FIG. 1 is a perspective top view of a container with center divider.

FIG. 2 is a perspective bottom view thereof.

FIG. 3 is a perspective top exploded view of the container with center divider.

FIG. 4 is a perspective top exploded view of the container with center divider in an alternate configuration.

FIG. 5 is a perspective bottom exploded view thereof.

FIG. 6 is a top exploded view of the container with center divider.

FIG. 7 is a top exploded view of the container with center divider in an alternate configuration.

FIG. 8 is a bottom exploded view thereof.

FIG. 9 is a front exploded view of FIG. 4, with the rear exploded view being a mirror image thereof; and,

FIG. 10 is a right-side exploded view thereof, with the left-side exploded view being a mirror image thereof.

The broken lines in FIGS. 1 and 3-8 show portions of the article and form no part of the claimed design.

1 Claim, 10 Drawing Sheets(56)
